EMBOSSING MEANS FOR ENVELOPE
MAKING MACHINES

Ferdinand L. Smithe, New York, N. Y., assignor
to F. L. Smithe Machine Co., Inc., New York,
N. Y., a corporation of New York

Application December 18, 1930, Serial No. 503,136
Renewed March 6, 1935

10 Claims. (Cl. 93—73)

This invention has to do with the embossing or embossing and printing of envelopes, and is illustrated herein as applied to the embossing and printing of stamps upon stamped envelopes.

It is not feasible to emboss the stamps upon the envelopes after the manufacture of the envelopes has been otherwise completed.

It has been the practice heretofore to emboss and print the stamps upon the envelope blanks before any other operations have been performed upon the blanks. This, however, involves the necessity of allowing the blanks time to dry before their actual manufacture into envelopes can be begun. It also involves the necessity of making provision from beginning to end of the envelope making machine for preventing the application of pressure by the operating parts and the feeding mechanisms to the embossed areas. It also precludes the use of a fan-out gumming mechanism for the sealing flaps.

In accordance with the present invention these difficulties are overcome by providing the printing and embossing mechanism as a part of the envelope making machine and at a point where all of the operations have been performed upon the blanks which can be performed with the blanks in a flat or unfolded condition. By this means, the parts which must be modified to avoid the application of pressure to the embossed area are greatly reduced in number while the embossing is effected in the most desirable and efficient way, that is to say, upon flat blanks.

It is a further feature of the invention that this printing and embossing mechanism is provided in a machine adapted to be adjusted for operating on blanks of various sizes, and that the introduction of new difficulties of adjustment is avoided by arranging for the printing and embossing means to operate in an invariable path, and by further arranging for adjustment of the blank feeding means to cause the printing and embossing means to occupy an invariable relation to the adjacent top and side edges of the body portions of the blanks regardless of their sizes. With this arrangement the cut-outs provided in the subsequent mechanism for avoiding contact with the embossed and printed area may be maintained in alignment with the fixed path of operation of the embossing and printing means so that lateral adjustment of such cut-outs is made unnecessary.

Other objects and advantages will hereinafter appear.

In the drawings forming part of this specification:

Figure 1 is a diagrammatic view in side elevation of a machine embodying features of the invention;

Figure 1a is a fragmentary, diagrammatic view showing a continuation of the machine beyond the parts shown in Figure 1;

Figure 2 is a fragmentary, sectional elevation of that portion of the envelope making machine including, and closely associated with, the embossing mechanism;

Figure 3 is a fragmentary view on a larger scale than Figure 2, showing stamp printing and embossing mechanism; and

Figure 4 is a plan view of the mechanism shown in Figure 2, certain parts being omitted for clearness of illustration.

The illustrative machine may be generally like the machine disclosed in the application of Abraham Novick, Serial No. 284,856, filed June 12, 1928, for Machine for making envelopes, now Patent No. 1,807,867.

Briefly, the machine includes means (not shown) for taking envelope blanks singly from a stack (not shown) and delivering them in timed relation onto a conveyor C which carries them around a drum D in fanned-out relation beneath a gummer G. From the conveyor C the envelope blanks are transferred, still in fanned-out relation, to a drier conveyor 2 from which the blanks are taken and fed at higher speed in spaced-out relation past an embossing mechanism E. The blanks are then subjected to the action of a scoring mechanism S and passed thence to a side flap folding mechanism 36, a gumming mechanism and a bottom flap folding mechanism.

The envelope blanks 1 on the conveyor 2 at the delivery end thereof are pushed forward by the conveyor 2 in overlapped relation along a table 3 face downward and with the sealing flap trailing. The conveyor 2 comprises a pair of chains 4 and 5 carrying gripper arms 6 which lie flat against the chains in blank gripping position as they travel along the table 3, but which are turned out at the delivery end of the conveyor tangentially of sprockets 7 and 8 to release the blanks as the chains pass around the sprockets 7 and 8. The sprockets 7 and 8 are normally fast upon a driven shaft 9. The chains 4 and 5 are so spaced from one another and are so timed with reference to the delivery of blanks to them that the grippers engage in the notches or re-entrant angles formed at the junctions of the sealing flaps 10 with the end flaps 11 of the blanks. Thus the blanks are pushed forward by the conveyor with-

out disalignment and in definitely timed and collated relation to one another even after the grip upon them has been released at the delivery end of the conveyor 2.

6 As the blanks are delivered by the conveyor 2, control of them is assumed by feeding segments 12a, 12b fast on a driven shaft 13, feed rollers 14a, 14b fast on a driven shaft 15, and a conveyor 16 which comprises chains 17 and 18.

10 The chain 17 runs upon a sprocket 19 fast on a driven shaft 20, a sprocket 21 loose on a driven shaft 22, and a sprocket 23 fast on shaft 15. The chain 18 similarly runs upon a sprocket 24 fast on shaft 20, a sprocket 25 loose on shaft 22, 15 and a sprocket 26 fast on shaft 15. The feed segments 12a, 12b, feed rollers 14a, 14b, and conveyor 16 all run at the same linear speed, this speed, however, being substantially greater than the speed at which the conveyor 2 travels.

20 The chains 17 and 18 are provided with upstanding pins 27 adapted to engage in the notches formed at the junctions of the sealing flaps 10 and the side flaps 11 of the blanks and the timing is such that a pair of fingers comes into engagement 25 with each blank at the points referred to just as these points cross the line of contact of segments 12a, 12b and rollers 14a, 14b.

Between the ends of the conveyor 16 provision is made of a printing and embossing couple for printing and embossing postage stamps, comprising a printing cylinder 28 fast on the shaft 22 and an impression cylinder 29 fast on a shaft 30. The engaging portions of these cylinders, or rather the dies carried by them, travel at the same linear speed as the conveyor 16 and make one complete revolution for each blank delivered by said conveyor. The pins 27 are accordingly spaced from one another at distances equal to the circumference of the impression roller 29. 40 The die 29a has a raised portion 29b for embossing a head or other figure, and the die 31 has a corresponding depression. The die plate 31 on the printing cylinder 28 is inked by means of an inking roller 32 and transfer rollers 33.

45 The blanks are delivered by the conveyor 16 to a scoring couple comprising a scoring roll 34 and a feed roll 35 and thence are passed to a side flap folding mechanism 36 which comprises a series of feed rollers 37, a series of co-operating feed rollers 38, and a pair of folding plates 39 and 40 for turning over the side flaps. The scoring mechanism scores the blank longitudinally and transversely along the lines dividing the body portion of the blank from the side and end flaps thereof. This mechanism is like that disclosed 50 in the application of Abraham Novick, Serial No. 348,749, filed March 21, 1929, for Scoring mechanism for use in envelope making machines, now Patent No. 1,839,492. Provision is, however, made of a recess 35a in roller 35 to avoid flattening out of the embossed head or figure forming part of the stamp. Recesses or cut-outs are provided for the same reason in all ensuing work engaging mechanism, wherever necessary.

60 It will be seen that with the mechanism described each pair of pins 27 of the conveyor 16 pushes a blank past the printing couple and that so long as the pins engage in the notches formed by the junction of the sealing flap with the side flaps the blanks will be presented to the printing couple so that the printing will appear on each blank at a uniform distance in advance of the pins. This relationship will be maintained regardless of the size of the blanks so long as a

proper widthwise adjustment is made whenever the size of the blanks worked on is changed, to make sure that the pins engage in the notches. Registration of the pins with the notches is independent of the size of the blank, being dependent upon the timing of the feeding segments 12a, 12b, with reference to the conveyors 2 and 16. The upper transverse fold line will also be marked invariably by the scoring mechanism in line with the points on the blank engaged by the pins, regardless of variations in the sizes of the blanks. 10

In order that the printing may be caused to bear a uniform relationship to a side edge of the face of each blank regardless of the size of the blank, and in order that the stamp may always 15 travel in line with the cut-outs or recesses formed in the subsequent work engaging members without necessity for adjustment thereof, provision is made in accordance with the present invention for maintaining the printing mechanism and all 20 of the feeding and guiding mechanism at one side of the blank unaltered for the various sizes of envelopes, and for making all lateral adjustments of the feeding and guiding mechanism at the opposite side. To this end the sprocket 1 25 is adapted to be secured in various adjusted positions along the shaft 9 by means of a set screw 41. The feed roller 14a is similarly adapted to be secured in different adjusted positions on the shaft 15 by means of a set screw 42 and the 30 sprocket 26 is adapted to be secured in different adjusted positions on the same shaft by a set screw 43. The feed segment 12a may be secured in different adjusted positions along the shaft 20 by means of a set screw 44 and similar adjustment may be made at one side of the scoring mechanism by means of a set screw 46. The arm which carries the folding plate 39 may be adjusted correspondingly by shifting the arm along the supporting bar 47 and then tightening 40 up nut 48 on a bolt 49 that extends through a slot in the supporting bar 47. The support 50 of the feed rollers 37 may be similarly adjusted by means of a bolt 51 and nut 52.

The bar 46a may be adjusted circumferentially 45 to increase or diminish the amount by which scoring blade 46b leads scorer 46c. Such adjustment does not, however, affect the timing of scorer 46c with reference to the feeding mechanism or the printer.

It will be seen that all the necessary adjustments are made without the necessity of disturbing the printing mechanism in any way, and with all the adjustments confined to one side of the machine. 55

From the scorer the blanks pass successively to the side flap folding mechanism 36, thence to gumming apparatus K for applying gum to the blanks, whereby the bottom flap will be gummed to the side flaps. From the gumming apparatus K, the blanks are passed to bottom flap folding mechanism L consisting of a pair of rolls 62, 63 running in contact, and a pair of cooperating folding blades 66, 67. The blanks are next passed to means M for folding the top flaps, and delivering the blanks from the folding mechanism consisting of a pair of feed rolls 70 and 71 and co-operating folding members 72, 73 for reversing the travel of the envelope and introducing the 60 sealing flap into the bight of feeding rolls 74, 71. The rolls 62, 63, 70, 71 and 74 are formed to escape engagement with the stamps.

While I have illustrated and described in detail a preferred form of my invention, it is to be 75

understood that changes may be made therein and the invention embodied in other structures. I do not, therefore, desire to limit myself to the specific constructions illustrated, but intend to cover my invention broadly in whatever form its principle may be utilized.

I claim:

1. In an envelope machine, the combination with means for gumming the sealing flaps of envelope blanks, means for drying the same, means for scoring the blanks along the edges of their body portions, means for folding in the side flaps, and means for folding in the bottom flaps and adhesively uniting them to the side flaps all arranged to operate on the blanks in the order named, of means for imprinting the blanks while the same are traveling from the drying means to the side flap folding means.
2. In an envelope machine, in combination, means for fanning out the envelope blanks and gumming the sealing flaps thereof while the blanks are in fanned-out condition, means for separating the blanks and advancing them at higher speed in definitely timed relation, imprinting mechanism operating in synchronism with the advancing means to imprint the blanks while they are being controlled and advanced by the advancing means, and means for thereafter folding in the side and bottom flaps of the blanks.
3. In an envelope machine, in combination, means for gumming and drying the sealing flaps of envelope blanks, means for thereafter embossing stamps in the corners of the body portions of the blanks while the blanks are still in flat condition, means for subsequently operating on the blanks to complete the envelopes, said stamp embossing means being operable in an invariable path for blanks of all sizes, and adjustable means for presenting the blanks to the embossing means with the upper and side edges adjacent the embossing area in substantially invariable relation to the embossing means for blanks of all sizes, and the subsequent operating means being constructed to escape engagement with the embossed area.
4. In an envelope machine, the combination with a gumming and drying mechanism, a scorer for transversely scoring the blanks, and a blank feeder for delivering the gummed and dried blanks to the scorer comprising blank pushing elements which bear invariable relation to the means for making the upper transverse score line, of rotary imprinting means, arranged to act on the blanks while under the influence of said feeder, the imprinting means and the pusher elements being arranged to act on the blanks in predetermined relation to one another.
5. The combination with means for gumming the sealing flaps of envelope blanks arranged in an overlapping band, means for drying the blanks while thus overlapped, means for separating the overlapped blanks, means for folding the flaps of the blanks to convert them into envelopes and means between said separating and folding means for imprinting the blanks.
6. The combination with means for gumming the sealing flaps of envelope blanks arranged in an overlapping band, means for drying the blanks while thus overlapped, means for separating the overlapped blanks, means for folding the flaps of the blanks to convert them into envelopes and means between said separating and folding means for imprinting the blanks, said imprinting means comprising an imprinting member for operating on the blank while the same is in motion.
7. The combination with means for gumming the sealing flaps of envelope blanks arranged in an overlapping band, means for drying the blanks while thus overlapped, means for separating the overlapped blanks, means for folding the flaps of the blanks to convert them into envelopes and means between said separating and folding means for imprinting the blanks, said means comprising a continuous carrier having members thereon for propelling and aligning blanks and rotary imprinting members for engaging the blank from above and below while the same is being carried by said continuous carrier.
8. The combination with means for conveying an overlapped series of blanks, of means for separating the blanks, a pair of rotary members for engaging the blanks above and below for acting on the separated blanks and a conveying device for conveying the separated blanks to said members, said conveying device having thereon means for propelling and aligning the blanks prior to their engagement by said rotary members.
9. The combination with means for gumming the sealing flaps of envelope blanks arranged in an overlapping band, means for drying the blanks while thus overlapped, means for separating the overlapped blanks, means for folding the flaps of the blanks to convert them into envelopes, and means between said separating and folding means for imprinting the blanks, said imprinting means comprising a pair of spaced continuous carriers having members thereon for propelling and aligning blanks and comprising also a pair of rotary imprinting members for engaging the blanks from above and below in the space between, and while on, said continuous carriers.
10. The combination with means for conveying an overlapped series of envelope blanks, means for gumming the sealing flaps of said envelope blanks while arranged in an overlapping band, means for drying the blanks while thus overlapped, means for separating the overlapped blanks, means for folding the flaps of the blanks to convert them into envelopes and means between said separating and folding means for imprinting the blanks, said imprinting means comprising a continuous carrier having members thereon for propelling and aligning blanks and comprising also a pair of rotary imprinting members for engaging the blanks from above and below while on said continuous carrier.
